Emil Franke
By *Victor J. Evans*,

Attorney.

UNITED STATES PATENT OFFICE.

EMIL FRANKE, OF LONG ISLAND CITY, NEW YORK.

PISTON-RING DEVICE.

1,316,705.

Specification of Letters Patent. Patented Sept. 23, 1919.

Application filed September 1, 1916, Serial No. 118,005. Renewed February 21, 1919., Serial No. 278,511.

To all whom it may concern:

Be it known that I, EMIL FRANKE, a citizen of the United States, residing at Long Island City, in the county of Queens and State of New York, have invented new and useful Improvements in Piston-Ring Devices, of which the following is a specification.

This invention relates to piston ring holding and contracting tools, and has for its principal object the provision of a tool of this character by means of which the packing rings of a piston can be eventually held in a contracted condition during the operation of placing the piston in the cylinder.

Another object of the invention resides in the provision of a device of this character which will include an adjustable ring embracing strap, which will accommodate itself to piston rings of various sizes.

With the above and other objects in view which will appear as the nature of the invention is better understood, the same consists in the improved construction and novel arrangements of parts which will herein-after be fully described and particularly pointed out in the claims.

In the accompanying drawings, has been illustrated, a single and preferred form of the invention, it being, however, understood that no limitations are necessarily made to the precise structural details therein exhibited, but that changes, alterations and modifications within the scope of the claims may be resorted to when desired.

Figure 1, is a perspective view of the tool.

Fig. 2, is a fragmentary plan view thereof, showing parts in section.

Fig. 3, is a perspective view of the detachable section of the clamping ring.

The invention consists of companion levers 1 and 2 pivoted at 3, they are free to rock one upon the other as will be understood.

The lever 1, is extended beyond the forward end of the lever 2, and it is provided with an angular lug 4, to which one end of a steel strip 5, is riveted or otherwise suitably secured as at 6.

The said steel strip 5, is provided with a longitudinal series of apertures 7, which are spaced at equal distances apart.

A heel 8 is provided at the end of the handle 2 and the said heel is provided with a convexed face best shown in Fig. 2. A

pin 8' is carried by the heel 8 and located near one end thereof and arranged substantially at an acute angle thereto.

In using the tool the operating ends of the handles 1 and 2 are first separated so that the spring strip can be freely placed over the piston and around the ring to be contracted. The free end of the ring or spring strip is then adjusted relatively of 60 the obtuse angular actuating pin upon the heel of the lever 2, when the levers 1 and 2 are drawn together by the hands of the operator, the said pin will be made to engage in one of the apertures in the spring strip, 70 and consequently the ring will be contracted, carrying with it the piston ring and thereby permitting the latter to freely enter the engine cylinder.

By providing the convexity upon the forward face of the heel 8, and through the fact that the pin 8' extends at an obtuse angle to said convexity, the free end of the apertured spring strip 5 of the section 9 will extend substantially at a tangent to the convexity so that the pin 8' will be free to immediately pass into an aperture of the strip or section when the 2 levers 1 and 2 are brought together.

In connection with the spring strip mentioned herein I employ a detachable section 9, having attaching tongues 10, stamped therefrom and adapted to be passed into a corresponding number of the apertures in the spring strip at the free end thereof, 80 thus forming a continuation of the spring strip and permitting the device to accommodate itself to large pistons as will be understood.

The section 9 is provided with apertures 95 similar to apertures 7 hereinbefore described in conjunction with the strip 5.

What I claim as new is:

1. A piston ring contracting device comprising two handle levers pivoted together 100 at points between their ends, one of the said levers having a working end portion which is larger than the working end portion of the other lever, the longer lever having at its end a laterally disposed lug which 105 is spaced from the adjacent end of the shorter lever, said shorter lever having a convexed heel disposed immediately opposite said lug, a pin carried projecting from said heel near one end thereof and adapted 110 to operate in the space between the ends of said lever and the lug, there being an un-

- obstructed entrance into the said space beyond the end of the shorter lever, and at one side of the longer lever, and a strip attached to the lug and having apertures 5 adapted to be engaged by the pin, the said strip being insertible edgewise through the said unobstructed entrance into the space between the end of the shorter lever and the lug, the end of said head nearest the 10 pin being adapted to press against said strip and arrange the same in position to receive said pin when the levers are actuated.
2. A piston ring contracting device comprising handle levers pivoted together at points between their ends, a convexed heel carried by one lever and provided near one end with a pin, a strip attached to the other lever and having apertures spaced at equal 20 distances apart, and a section having apertures adapted to be engaged by said pin, the said section also having spaced tongues stamped therefrom and adapted to engage in the apertures of the said strip.
3. A piston ring adjusting and contracting tool, comprising two pivoted levers, a contracting element carried by one of said levers and consisting of a plurality of ad- 25 justably connected sections, and means on the other lever co-acting with said sections to contract said member.
4. A piston ring adjusting and contracting tool, comprising two pivoted levers, a flexible contracting element consisting of a main section fixed at one of its ends to 35 one of said levers and an auxiliary section having separable connection with the first section and adapted for free passage between the adjacent ends of both levers, the other lever having means co-acting therewith to effect adjusted conditions of said element.
5. A piston ring adjusting and contracting tool, comprising two pivoted levers, a flexible contracting member consisting of a 45 main section having a longitudinal series of perforations, said section having permanent connection at one end with one of the levers, a second section having means adapted for interchangeable connection in 50 the perforations of the first section, and means on the other lever co-acting with said second section to effect a drawing action thereon, as and for the purpose specified.

In testimony whereof I affix my signature. 55
EMIL FRANKE.
